ATTORNEY S

UNITED STATES PATENT OFFICE.

LEWIS C. MORGAN, OF CANTON, OHIO, ASSIGNOR OF ONE-HALF TO WILLIAM J. PIERO, OF SAME PLACE.

CONNECTING-ROD.

SPECIFICATION forming part of Letters Patent No. 442,293, dated December 9, 1890.

Application filed March 10, 1890. Serial No. 343,301. (No model.)

To all whom it may concern:

Be it known that I, LEWIS C. MORGAN, a citizen of the United States, residing at Canton, in the county of Stark and State of Ohio, have 5 invented certain new and useful Improvements in Connecting-Rods; and I do hereby declare that the following is a full, clear, and exact description of the same, reference being had to the annexed drawings, making a part 10 of this specification, and to the letters of reference marked thereon, in which—

Figure 1 is an isometrical view. Fig. 2 is a side elevation showing parts in section. Fig. 3 is a side elevation showing the retaining-rods removed. Fig. 4 is a view showing the outer cap or box designed and calculated to be located at the reciprocating end of the connecting-rod, showing portions of the retaining-rods.

20 The present invention has relation to connecting-rods; and it consists in the different parts and combination of parts, hereinafter described, and particularly pointed out in the claims.

25 Similar letters of reference indicate corresponding parts in all the figures of the drawings.

In the accompanying drawings, A represents the main rod or bar, to which is securely 30 attached the heads or blocks B and B'. The retaining-rods C C are located substantially as shown in the drawings, and are securely attached to the block D, substantially as illustrated in Fig. 2. For the purpose of preventing any accidental displacement of the block D, the screw-threaded ends located in said block D and the portion of said screw-threaded ends, which extend beyond the outer face 35 of said block D are headed or swaged.

40 The head or block B is provided with the grooves a, which are for the purpose of receiving the retaining-rods C C, substantially as illustrated in Figs. 1 and 2. The opposite ends of the retaining-rods C C are screw-threaded, as shown in the drawings, said screw-threaded portions being for the purpose of receiving the thimble-nuts D', substantially as illustrated in the drawings. The thimble-nuts D' are received in the apertures b, which 45 apertures b are formed somewhat larger in 50 diameter than the apertures b', thereby form-

ing the shoulders or ledges c. The outer ends of the thimble-nuts D are provided with the heads d, which in this instance are provided with the apertures d', which apertures are for 55 the purpose of receiving the end of a rod to turn the thimble-nuts D'; but it will be seen that the same object can be accomplished by means of an angular head and a wrench; but I prefer to use the device shown to turn the 60 thimble-nuts D'. These thimble-nuts D' are open at both ends, one end being for the purpose of receiving the adjusting-bolts E.

In use, when it is desired to tighten or take up the wear at the boxing of either the crank-pin or cross-head bar, the adjusting-bolts E are turned a short distance, so as to bring their inner end away from the screw-threaded ends, at which time the thimble-nuts D' are turned so as to draw or pull on the retaining-rods C C, thereby bringing the block D and the block F toward each other, which in turn takes up any looseness which may be at either end of the connecting-rod proper.

It will be seen that in case the boxing proper 75 is loose only at one end the looseness will be taken up, and that it is not necessary to determine at which end the looseness is before tightening. It will also be seen that the tightness of the bearing or boxing at each end 80 of the connecting-rod proper will be the same. When the boxing has been properly adjusted as to tightness, the adjusting nuts or bolts E are turned inward until their inner ends abut against the screw-threaded ends G of the retaining-rods C C. The thimble-nuts D' are so 85 adjusted that their inner ends will abut against the shoulders or ledges c, thereby providing a stop for said thimble-nuts and allow the retaining-rods C C to be drawn endwise, and 90 at the same time drawing the blocks B and D together in the event there is any looseness between said blocks B and D, and in the event there is any looseness between the blocks B' and F the block F will be forced toward the 95 block B', thereby taking up any looseness which may be between said blocks B' and F. The block F is forced toward the block B' by means of the inner ends of the thimble-nut bearing against the shoulders or ledges c.

I prefer to adjust the heads d so that they will bear upon the block F, thereby providing

two bearing-points for each of the thimble-nuts D'.

It will be understood that the connecting-rod proper above described is calculated and 5 designed to be used in steam-engines or in other machinery employing connecting-rods having boxing upon each end of the connecting-rod.

Having fully described my invention, what 10 I claim as new, and desire to secure by Letters Patent, is—

1. The combination of the main bar or rod A, having attached thereto the heads or blocks B and B', the retaining-rods C C, the thimble-nuts D', the adjusting-bolts E, the blocks F and D, substantially as and for the purpose specified.

2. In a connecting-rod, the combination of 15 the retaining-rods C C, having the screw-

threaded ends, as G, the thimble-nuts D', the block F, having the ledges e, the block D, and the adjusting-bolts E, substantially as and for the purpose specified.

3. The block B, provided with grooves a, the block D, the retaining-rods C C, fixed to the block D, the main rod A, having fixed thereto the blocks B and B', the block F, provided with the apertures b and b', the thimble-nuts D', provided with the heads d, having apertures d', and the adjusting-bolts E, substantially as 30 and for the purpose specified.

In testimony that I claim the above I have hereunto set my hand in the presence of two witnesses.

LEWIS C. MORGAN.
